UNITED STATES PATENT OFFICE

155,461

DESIGN FOR A NOTION DISPLAY CASE

Josephine F. Sylvia, New Bedford, Mass.

Application November 25, 1946, Serial No. 135,075

Term of patent 14 years

(Cl. D80—9)

To all whom it may concern:

Be it known that I, Josephine F. Sylvia, a citizen of the United States of America, residing at New Bedford, in the county of Bristol and State of Massachusetts, have invented a new, original, and ornamental Design for a Notion Display Case, of which the following is a specification, reference being had to the accompanying drawing, forming a part thereof, wherein:

I claim:

The ornamental design for a notion display case, as shown.

JOSEPHINE F. SYLVIA.
